UNITED STATES PATENT OFFICE.

GEORGE WALTHEER, OF DAYTON, OHIO, ASSIGNOR TO THE DAYTON STEEL FOUNDRY COMPANY, OF DAYTON, OHIO, A CORPORATION OF OHIO.

APPARATUS FOR CASTING STEEL WHEELS.

Application filed June 5, 1920. Serial No. 386,850.

To all whom it may concern:

Be it known that I, GEORGE WALTHEER, a citizen of the United States, residing at Dayton, in the county of Montgomery and State of Ohio, have invented certain new and useful Improvements in Apparatus for Casting Steel Wheels, of which the following is a specification, reference being had therein to the accompanying drawing.

10 My invention relates to casting steel wheels, and in particular to a method and apparatus for this purpose.

My apparatus and method are directed to meeting the problem of quantity production of cast steel wheels, primarily for automotive equipment. In order to facilitate this production, I have found it essential to reduce the number of operations in making the cores and to provide a ready means for assembling and disassembling the cores. It is also an object of my invention to use cores of either green or dry sand. It is possible by my invention to use green sand entirely for the cores, forming the spokes and rim. It is another object of my invention to provide a method of manufacture which shall reduce the necessity for the employment of skilled labor in casting wheels of this character.

30 Referring to the drawings, Figure 1, is a plan view of the supporting arbor, and the cores;

Fig. 2, is a plan view of a core carrying frame used for adjusting the units of the core in position;

Fig. 3, is a side elevation of a vertical section showing the cores in position prior to the casting of the wheel with the core carrying frame positioning the cores; and

40 Fig. 4, is a view of a flask with the cores in position, showing in section the supporting arbors for the cores.

Referring to Figure 1, it will be observed that there is an outer ring 1 divisible at 45 points 2-2 into segments, a complete set of segments completing the circle. To each segment of the ring is connected at an angle thereto the arbor 3 with projections 4 thereon to support the sand of the rim and spoke core 5. The bridges of the metal wheel forming a part of its outer rim are seen at 50 6-6 while the inner wall of the rim is at 7. The wall of the spokes is 8. The hub core is at 9, supported by the arbor 10. The 55 arbor 10 of the hub and the arbor 3 of the

spokes are connected to one another at 11 in any suitable manner.

The core for the spokes and rim and the hub is supported by the arbor 3 and is made up either of green or dry sand, with the 60 arbor 3 imbedded therein. 12 is a hook attached to the segment of the supporting frame, the use of which will be described in connection with Figures 2 and 3.

Referring to Figure 2, we see an annular 65 carrying frame 13 with handles 14-14. Across the frame are braces and supporting members 15. Centrally located is a clamping hook 16 rotated and thereby depressed or elevated by the hand wheel 17. The purpose of this hook is to clamp the arbor 10 and the arbors 3 to the frame 13, as will be more clearly seen in Figure 3. Above the members 5 is a central spacing block 18 which serves to assist in clamping the cores 70 and their arbors in position. On the periphery of the ring 13, in Figure 2, will be seen another clamping hook 19 and its hand wheel 20 which is used to clamp in position the ring 1 seen in section in Figure 3. The 75 hook 19 engages with the hook 12 on the ring 1 so that the clamping can be readily effected by rotating the wheel 20. Only one of these hand wheels and hooks on the periphery of the ring 13 is shown. Corresponding wheels are located on this ring for the other spokes depending upon the 80 number of spokes. The installation shown is typical of the arrangements.

In Figure 3, 21 is the flask wall and 22 90 the sand suitably impressed by the pattern adapted for this purpose, to determine the location of the outer wall of the wheel. 23 is a positioning pin of the carrying frame. This pin passes through the aperture 24 in 95 the lug 25 of Figures 2 and 3. This pin 23 projects through a spacing block 26 and a portion of the flask 21 at 27. By this standardized arrangement I am enabled with relatively unskilled labor to quickly position 100 the respective elements of the cores, to utilize green sand and upon the casting of the wheel to withdraw the rings and the spoke arbors for use at another time. The hub arbor becomes an integral part of the wheel and is 105 broken away upon the completion of the casting. The only loss is the hub arbor, new ones of which are employed for each of the castings.

In Fig. 4, is shown a flask, cores, etc., in 110

section. It illustrates also the method of connection between the spoke arbor and the hub arbor. In one instance it is adjustable and in the other instance it is merely a depression in the spoke arbor to receive the projection of the hub arbor.

I desire to comprehend within the scope of my invention its equivalents and the modifications that are within its scope.

10 Having thus fully described my invention, what I claim as new and desire to secure by Letters Patent, is:—

1. In an apparatus for moulding, a plurality of segments constituting a circular body, an arbor attached to each of said segments, the inner ends of each of said arbors being adapted to embrace a central hub arbor, and a hub arbor.

2. In an apparatus for moulding a plurality of segments constituting a circular body, an arbor attached to each of said segments, the inner ends of each of said arbors being adapted to embrace a central hub arbor, a hub arbor, means on each of said segments for clamping them in position and means on said hub arbor for clamping it in position.

3. In an apparatus for moulding, a plurality of segmental sections, an arbor at-

tached to each of said sections projecting inwardly to a common center, a plurality of projections on said arbors, means on the inner end of said arbors to engage a hub arbor, a hub arbor and a plurality of depending fingers on said arbor whereby the inner ends of the spoke cores may be supported while the casting occurs.

4. In an apparatus for casting wheels, a segment of a ring, an arbor adjacent said segment, a plurality of projections throughout the length of said arbor and means on the inner end thereof for engaging a hub arbor, a hook attached to said segment on the inner side thereof, a core surrounding said arbor and adjacent to said segment, a hub core and a hub arbor therein cooperating with the spoke arbor whereby the spoke arbor positions the hub arbor and core.

5. In an apparatus for molding, a plurality of segments constituting a circular body, an arbor attached to each of said segments, the inner ends of each of said arbors being adapted to embrace a central hub arbor, a hub arbor, and cores carried by said segments and said arbors.

In testimony whereof, I affix my signature.

GEORGE WALTHER.
